UNITED STATES PATENT OFFICE.

SIMON P. GRANT, OF NEW WESTMINSTER, BRITISH COLUMBIA, CANADA.

LINEMAN'S LIFTING AND HOISTING DEVICE.

Application filed October 1, 1926. Serial No. 138,891.

This invention relates to a lifting and hoisting device for linemen and others concerned with the mounting of heavy objects on poles, as for instance the installing of 55 transformers on the poles which support electric conductors.

Its object is to provide a handy, portable apparatus which a lineman can take with him without impediment and so obviate the 10 necessity for the use of cumbersome lifting tackle.

The raising of a heavy transformer near to the top of a high pole and the subsequent maneuvering of the same into correct position 15 frequently requires the use of devices of no inconsiderable weight and bulk, and my device is designed to eliminate this disadvantage thus saving delay, cost and trouble.

20 I effect these results by the adoption of a pivotal lever of the first order, carried by a fulcrum which is clamped to the pole at or near its upper extremity. At one end of the lever is secured a block and tackle in connection with the load to be raised; at the other end is a hauling cable. The position 25 of the latter attachment affords a leverage of say two to one on the load. Guy-ropes on each side attached, say mid-way of the fulcrum and the haulage cable complete the 30 elements of the device.

In the drawings herewith, which form 35 part of this application, Fig. 1 is a general elevation of the device showing the disposition of the salient parts in their working position; Fig. 2 is a side elevation of the bifurcated clamp for carrying the lever; and Fig. 3, a plan view of same, both being to an enlarged scale as compared with the 40 view in Fig. 1.

The top end of the line pole 1 carries a substantial clamp 2 which is formed in halves and bifurcated at 3 to receive the lever 4 which may conveniently consist of 45 a standard hard-wood cross-bar. This latter pivots at the fulcrum 5 and carries at its longer end 6 a haulage rope attachment, and also at 7 eyes for the guy ropes 8 and 9, with a link at 10 for the block and tackle 11. 50 Part of a suspended transformer is shown at 12, which, when the haulage rope 13 is slackened, assumes a vertical position below

the dotted lines 14 of the lever 4, and can then be swung towards or slightly around the pole 1, the guy ropes being utilized for 55 steadyng effect should this be necessary.

The anchor-spike 15 functions to prevent any tilting effect on the clamping ring 2 when the load comes on the fulcrum 5. It is secured at a suitable angle as shown and 60 tends to pierce the wood, thus preventing any appreciable angular movement of the clamp about the pivot 5.

Having now particularly described my invention, what I desire to be protected in by 65 Letters Patent is:—

1. In a lineman's pole hoisting device of the character described the combination comprising, a clamping member adapted to encircle a post, said member having a radial projection, said projection being forked at its extremity, said fork being spanned by a fulcrum pin, a lever of the first order pivoted on said pin, a hauling cable attached to one extremity of said lever, and 70 a block and tackle attached to the other.

2. In a lineman's hoisting device for a pole, the combination comprising, a clamping member adapted to encircle a post, said member being in two similar semicircular 80 parts bolted together at two diametral and lateral extensions of said semicircular parts, said member having a radial extension formed by the prolongation of said lateral extensions, said radial extension being 85 forked, said fork being spanned by a fulcrum pin, a lever of the first order pivoted on said pin, a block and tackle secured to the shorter end of said lever, a hauling rope attached to the longer end of said lever, guy 90 ropes attached to said lever on each side thereof, all substantially as described and shown.

3. A lineman's lifting and hoisting device 95 for pole service, comprising, a clamping ring adapted to encircle a pole, said ring being formed in halves with lateral diametral extensions for bolting together, one pair of said lateral extensions being prolonged and forming an extension radial to said pole, said radial extension being bifurcated at its extremity, the said bifurcation being spanned by a fulcrum pin, an anchor-spike 100 angularly disposed to said pole and secured

to said lateral extension of clamping-ring on side of said pole opposite to said fulcrum and adapted to pierce the said pole by the action of a downward strain on said fulcrum, a lever of the first order fulcrumed upon said pin, a haulage rope attached to the longer end of said lever, and a block and

tackle attached to the shorter end of said lever, all substantially as described and shown.

10

In testimony whereof I affix my signature.

SIMON P. GRANT.
